Filed Jan. 28, 1963, Ser. No. 254,307
10 Claims. (Cl. 93—93)

The present invention relates to a method and apparatus for conveying, stacking and counting papers delivered by a folder, operating either as a separate machine, or as the final unit of a sheet or web-fed perfecting press. The primary object of the invention is to provide a new and improved apparatus for elevating the papers from the usual low-level delivery point on the folder or press, to a convenient height for removal by the operator, and also stacking the papers into stacks, each of which contains an exact specified count of papers. The term "papers" as used herein includes signatures, newspapers, folders, brochures, and the like.

Another important object of the invention is to provide an apparatus of the class described which is extremely compact, and requires a minimum of floor space. This is an important consideration in many publishing firms, where floor space is limited and incapable of being expanded.

A further object is to provide a conveyor-stacker-counter that is capable of operating at high speed to handle the output of the highest speed folders and web-fed perfecting presses in use at this time.

Another object is to provide a conveyor-stacker-counter that is easily adaptable to various makes and models of folders and presses, and that is capable of handling all sizes and types of material within the capacity of these machines.

These and other objects and advantages of the invention will become apparent to those skilled in the art upon consideration of the following detailed description of the preferred embodiment thereof, shown in the accompanying drawings, wherein:

FIGURE 1 is a top plan view of a conveying, stacking and counting apparatus embodying the principles of our invention;

FIGURE 2 is an enlarged sectional view of the same, taken at 2—2 in FIGURE 1;

FIGURE 3 is a partially cut-away elevational view of the machine, as seen from the side opposite that shown in FIGURE 2;

FIGURE 4 is a fragmentary sectional view, taken at 4—4 in FIGURE 3; and

FIGURE 5 is an enlarged fragmentary sectional view, taken at 5—5 in FIGURE 2.

The machine shown in the drawings comprises a supporting frame structure 10 standing on legs 11. The frame structure 10 consists of laterally spaced pairs of horizontal top and bottom members 12 and 13, which are connected together by vertical members 14 and 15, and transverse angle irons 16. The frame is enclosed by side plates 17, end plate 18, and top plate 19, which strengthen the structure and enclose the operating mechanism. The frame is completed by two vertically spaced, horizontal table surfaces 20 and 21, the top table 20 constituting a loading table, and the bottom table 21 constituting a receiving table.

As best shown in FIGURES 2 and 3, the bottom table 21 is flush with the top surface 22 of a conveyor 23, comprising a part of a holder (not shown) operating either as a separate machine or as the last unit of a sheet or web-fed perfecting press. The printed, assembled and folded papers are delivered by the conveyor 23 in a continuous line 24 of overlapping papers, which are initially

2

disposed with their leading edges exposed and overlying the trailing edges of the papers ahead. The conveyor 23 is usually in the form of a belt conveyor having a plurality of laterally spaced endless belts 25, only one of which can be seen in FIGURE 2. These belts 25 are trained around pulleys, one of which is shown at 26 in FIGURE 2, and pulleys 26 are mounted on a rotatable shaft 30, journaled in suitable bearings mounted on side bars 31 forming a part of the supporting frame of conveyor 23. The bottom frame members 13 of our machine overlie the ends of the side bars 31 and are attached thereto by screws 32, thereby tying the machine to the conveyor 23.

The machine includes a drum 33 of relatively large diameter extending substantially the full width of the frame 10 adjacent one end thereof, and an idler 34 of much smaller diameter extending between and rotatably supported on the top frame members 12. The drum 33 has circular end plates 35 and 36 that are mounted at their centers on a horizontal shaft 40; the latter being journaled at its ends in bushings 41 (see FIGURE 5), contained within tubular bearing supports 42, which abut against the inner surfaces of vertical frame members 14, and are attached thereto by screws 43. The tops of the drum 33 and idler 34 are substantially tangent to the plane of the top table 20, and the bottom of the drum is substantially tangent to the plane of the bottom table 21.

The idler 34 may be a single roller, or it may consist of a plurality of axially aligned rollers, which are spaced apart on a shaft 44, as in the illustrated embodiment. The shaft 44 is journaled at its ends in bearings 45, which are mounted on inside faces of the top members 12.

A group of three laterally spaced, endless belts 46 is trained around the drum 33 and idler pulley 34, with the top flight of the belts resting on and sliding over the loading table 20. Another group of three laterally spaced, endless belts 47 is wrapped around the right-hand side of the drum 33, as viewed in FIGURE 2, and are trained around a series of rollers 50, 51, 52 and 53, which are arranged as shown. Each of the rollers 50, 51, 52 and 53 comprises a plurality (in this case, three each) of separate rollers rotatably mounted on supporting shafts, which extend transversely across the width of the frame 10 and are supported at their ends in suitable bearings mounted on the frame.

The two series of conveyor belts 46 and 47 cooperate to form a conveyor having a receiving end at 54 and a discharge end at 55. The former is disposed to receive the line of papers 24 discharged by the conveyor 23, and the latter is disposed to deliver the said papers to a stacking station, designated generally at 56, on the loading table 20. Between the drum 33 and rollers 50, the belts 47 rest on and slide over the bottom table 21, providing a short horizontal section of conveyor length along which the papers 24 travel before being engaged by the belts 46. The purpose of this will be explained presently.

The conveyor belts 46, 47 and the drum 33 are driven at a fixed speed ratio with respect to the operating speed of the folder or press, by means of a drive chain 60, which is trained around sprockets 61 and 62, mounted on shafts 30 and 63, respectively. Shaft 30 is the end pulley shaft of the conveyor 23, and is driven by the folder or press at a speed directly proportional to the operating speed of the said machine. Preferably, the sprocket 62 is slightly larger than the sprocket 61 (of the order of 16 teeth for sprocket 62, to 13 teeth for sprocket 61, for example), so that the belts 47 are driven at a slightly slower speed than the belts 25 of the conveyor 23. This causes the papers to bunch together slightly as they are transferred from the conveyor 23 to the conveyor belts 47, which makes for easier

stacking of the papers. The belts 46 and drum 33 are frictionally driven by the belts 47 with little or no slippage, and the conveyor mechanism of the present machine is thus driven at a certain fixed speed ratio with respect to the operating speed of the associated folder or press.

The conveyor belts 47 are drawn tightly around the drum 33 and rollers 50, 51, 52 and 53, by means of a tensioning device 64, which is incorporated into the rollers 52. The said tensioning device is an arrangement for mounting the rollers 52 so that they can be moved inwardly from their normal operating position to release the tension in the belts 47, together with means for spring-loading the rollers so that they are urged outwardly to take up any slack in the belts. The chief purpose of this tensioning device 64 is to allow the belts 47 to yield away from the belts 46 where they are both wrapped around the drum 33, so as to accommodate thick, bulky papers, as well as thin papers.

The tensioning device 64 consists of a pair of crank arms 65, which are swingably supported at one end on a pivot shaft 66; the latter being fixedly secured to plates 67 on the frame structure 10. Shaft 70, on which pulleys 52 are rotatably supported, is mounted at its ends in the free-swinging ends of the crank arms 65. Torsion springs 71 are wrapped around the pivot shafts 66 and are hooked over their respective crank arms 65 to urge the latter in the clockwise direction, as viewed in FIGURE 2. The springs 71 are anchored at their other ends to the plates 67.

In traveling around the right-hand side (FIGURE 2) of the drum 33, the line of papers 24 is elevated to the height of the loading table 20 and also inverted, so that the leading edge of each paper underlies the trailing edge of the paper ahead. This is an important step in the operation of the machine, as it enables the stacks to be built up by inserting the papers into the bottom end of the stack, thereby causing the stack to rise in place without the necessity of any lowering device, such as is required when papers are added to the top end of the stack.

As the line of papers 24 passes out from under the top rollers 53 and approaches the stacking station, the papers are engaged at their leading edge by a stop means 72, which is movable between the extended position shown in solid lines in FIGURE 2, and the retracted position shown in broken lines. The stop means 72 preferably comprises a bar 73, which extends transversely across the frame just beneath the loading table 20. The bar is attached at its ends to the ends of two pivoted lever arms 74 and 75 extending generally lengthwise of the top frame members 12. Fingers 76 project upwardly from the bar 73 through slots 80 in the loading table 20 beneath the belts 46 and at the outside thereof.

Lever arm 74 is pivotally supported at the end opposite the bar 73 on a transverse shaft 81, which is mounted at its ends on the frame members 12. Lever arm 75 is longer than lever arm 74, and is pivotally supported near its mid-point on the shaft 81. A spring 82 urges the stop means 72 up to the extended paper-engaging position, and the said stop means is periodically retracted by cam means 83 that will now be described, to allow the completed stacks of paper to move clear of the stacking station 56.

The cam means 83 of the illustrated embodiment, is an arrangement giving the machine an element of flexibility with respect to the count of papers going into each stack. With the machine shown herein, stacks can be built with any one of three specified counts, such as 25, 50 or 100, the exact numbers being dependent upon certain dimensions of the machine, but the ratios of the three stack counts with respect to one another being 1, 2 and 4.

Cam means 83 comprises a rotatable base member 84 mounted on end plate 35 of the drum 33. The base

member 84 is a circular plate that is bolted to one face of a sprocket 85, so that it stands out slightly from the face of the latter, as shown in FIGURE 5. The sprocket is journaled on a bushing 86, which is mounted on a shouldered bolt 87 that is secured to the drum end plate 35. A drive chain 88 is trained around the sprocket 85 and around a second, much smaller, stationary sprocket 90 formed integrally with the tubular bearing support 42. The diameter of the smaller sprocket 90 is one-fourth the diameter of the larger sprocket 85, so that the latter turns in a clockwise direction (FIGURE 2) at one-fourth the speed of the drum 33 when the latter turns in a counter-clockwise direction.

Four equi-angularly spaced, radial slots 91 are provided in the base member 84, and slidably disposed within these slots are cam lobes 92, which may be secured by means of bolts 93 at either an operative or inoperative position. The operative position for the lobes 92 is at the outer ends of the slots 91, while the inoperative position is at the inner ends thereof.

The cam lobes 92 are engageable with the arcuately curved underside 94 of a pivoted cam member 95, the curved outer surface 96 of which is engageable by cam followers 97 and 98 on the end of the lever arm 75 opposite the bar 73. The cam member 95 is pivoted at 99 on the drum end plate 35, and when the underside 94 is engaged by one of the cam lobes 92, the cam is swung upwardly to a position where the outer surface 96 engages the cam followers 97, 98 as the cam passes under them.

30 A spring 100 pulls the cam 95 inwardly against an angle bracket stop 101 on the drum end 35 when the cam is not lifted by one of the lobes 92, and in this inwardly retracted position, the cam clears the followers 97, 98 and does not actuate the stop means 72. The two cam 35 followers 97, 98 are spaced along the length of the lever arm 75 so as to extend the length of time that the stop means 72 is retracted without lengthening the cam 95 excessively. The number of cam lobes 92 is an even-numbered plurality, such as 2, 4 or 6, and the ratio of 40 the diameter of the large sprocket 85 to the diameter of the small sprocket 90 must have the same numerical value. Thus, the base member 84 is driven by the sprockets 85, 90 at a rotational speed that is a fraction of the drum rotational speed, the said fraction being the reciprocal of the number of cam lobes 92.

The underside 94 and outer surface 96 of the cam member 95 are concentric arcs, the centers of which are at the axis of rotation of the drum 33 when the cam member is lifted by the lobes 92. Thus, once the cam 50 member 95 has been lifted by one of the lobes 92, the position of the cam remains unchanged as the lobe moves along the underside 94, while at the same time, the outer surface 96 remains at a fixed position for the entire period of time that one or both of the cam followers 97, 98 is engaged. The cam followers 97, 98 are preferably 55 rollers journaled on the lever arm 75, although stationary shoes would be used in their place. While it is the cam 95 that is engaged by the followers 97, 98, it will be apparent that the cam 95 is nothing more than an extension of the operative lobes, and it is actually the operative cam lobes 92 that are responsible for lifting the followers.

When the stop means 72 is retracted by the cam means 65 the completed stack of papers is carried along the loading table 20 by the belts 46 until it clears the stacking station 56, at which point the stop means 72 is restored to its extended, paper-engaging position to start the next stack.

In order to allow the stop means 72 to pass upwardly 70 through the line of papers 24, gaps are opened up between successive papers in the line, and the stop fingers 76 are inserted up through these gaps. The means for opening up these gaps may be termed an intercepting means, and is designated as such by the reference numeral 105. The intercepting means 105 consists of a pivoted, plate-like

member 106 disposed above the bottom table 21 and extending transversely to the belts 47. The member 106 has downwardly projecting fingers 107 that are spaced apart laterally to allow the belts 46 to pass between them. The member 106 is attached to a shaft 108, which is 5 journaled at its ends in hangers 110 that project downwardly from the frame members 12. An arm 111 projects from the shaft 108, and a tubular member 112 is pivoted on the outer end of the arm.

Passing through the tubular member 112 and slidably 10 freely therethrough is a vertical rod 113, the bottom end of which is threaded to receive two nuts 114 that are spaced apart a distance to receive a compression spring 115 therebetween. The upper end of the rod 113 is likewise threaded, and is passed through a hole in one end of a pivoted 15 lever arm 116. Nuts 120 are screwed onto the threaded top end of the rod on opposite sides of the arm 116 to provide a loose connection between the rod and the lever arm.

The lever arm 116 is pivoted intermediate its ends on 20 the shaft 81, and cam followers 120 and 121 are provided on the end of the arm opposite the rod 113, which are engageable by another cam means 122 on the end plate 36 of the drum. The cam means 122 and associated cam member 123 are identical to the cam means 83 and cam 25 member 95 just described, and therefore will not be described in detail again; the only differences being a slight angular displacement between them, about the drum axis as a reference, and a slight difference in the length of the working surfaces on the cams 95 and 123. Cam 123 30 is somewhat longer than cam 95 to give a longer dwell time for the intercepting means 105 than for the stop means 72. The cam means 83 leads the cam means 122 slightly, causing the stop means 72 to be retracted a moment before the intercepting means 105 is swung downwardly. A compression spring 118 bears downwardly 35 against the left-hand end (FIGURE 3) of the lever arm 116, causing the right-hand end thereof to abut against an angle bracket stop 119 when the cam followers 120, 121 are disengaged from the cam member 123.

The intercepting means 105 is actuated by the cam means 122, and is swung downwardly to the position shown in phantom lines in FIGURE 3, where the fingers 107 engage the exposed leading edge of the papers on the conveyor belts 47 and hold the same back, while the 45 papers that have passed beyond the fingers 107 are carried along by the belts 47 to open up a gap.

To facilitate extraction of the paper just preceding the one engaged by the fingers 107, from beneath the stopped papers, means is provided for pressing the said preceding paper down against the belts 47 to obtain more traction therewith. The means for accomplishing this is preferably in the form of two small rollers 124 carried at the ends 50 of leaf springs 125, which are attached to the member 106 in positions such that the rollers 124 ride on two of the belts 47. The leaf springs 125 cause the rollers 124 to press the papers downwardly against the belts 47 with a light spring pressure, and this gives the belts 47 additional traction on the paper to pull it from under the stopped paper.

Additional traction between the papers and the belts 46 is also provided beyond the roller 53, where the papers are inserted into the bottom end of the stack. Here the problem is one of obtaining enough traction on the last paper to pull it all the way into the bottom of the stack, as the stationary paper just above exerts a retarding effect on the last paper, and there is no overlying paper to help hold the last paper down against the belt. In this case, traction is provided by three small wheels 126 that are 55 journaled on the ends of arms 127, which are pivotally supported at their other ends on a shaft 128 for vertical swinging movement. The arms 127 are curved to pass over the rollers 53, and the weight of the arms and wheels 126 causes the latter to press the trailing edge of the last 70 paper down against the belts 47 for increased traction therewith.

While we have shown and described in considerable detail what we believe to be the preferred embodiment of our invention, it will be understood by those skilled in the art that various changes may be made in the shape and arrangement of the several parts thereof, without departing from the broad scope of the following claims.

We claim:

1. Apparatus for conveying and stacking papers received from a machine into stacks of a predetermined number of copies, comprising:

a horizontal loading table;

conveyor means disposed to receive a continuous line of overlapping papers from said machine and transport the same onto said loading table, said papers being initially disposed with the leading edge of each paper exposed and overlying the trailing edge of the paper ahead;

said conveyor means including means for inverting the line of papers so that the leading edge of each paper is overlaid by the trailing edge of the paper ahead; stop means engageable with the leading edge of said papers as they are discharged onto said table, whereby said papers are stopped and caused to accumulate into a stack, said papers being inserted into said stack at the bottom end thereof;

intercepting means engageable with the exposed leading edge of one of said papers ahead of said inverting means, for momentarily stopping the papers so as to open up a gap between the leading edge of said one paper and the trailing edge of the paper just ahead; the distance between gaps being such that the predetermined number of papers to be inserted into each stack is carried by said conveyor means between them;

means operable to remove said stop means from its engagement with said papers on said loading table for a time interval sufficient to allow the stack to move along the table to a point clear of said stop means, and then return said stop means to engage the leading edge of the next succeeding paper following a gap opened up by said intercepting means; and means operable to move said intercepting means into engagement with said papers in synchronism with the removal of said stop means, whereby the gap opened up in the line of papers by said intercepting means reaches said stop means as the latter moves into operative position after releasing a stack.

2. Apparatus for conveying and stacking papers received from a machine into stacks of a predetermined number of copies, comprising:

a horizontal loading table;

belt conveyor means disposed to receive a continuous line of overlapping papers from said machine and transport the same to a stacking station on said loading table, said papers being initially disposed with the leading edge of each paper exposed and overlying the trailing edge of the paper ahead;

said belt conveyor means including means for inverting the line of papers so that the leading edge of each paper is overlaid by the trailing edge of the paper ahead as said papers approach said stacking station;

stop means engageable with the leading edge of said papers as they are brought to said stacking station, whereby said papers are stopped and caused to accumulate into a stack, said papers being inserted into said stack at the bottom end thereof;

intercepting means engageable with the exposed leading edge of one of said papers ahead of said stacking station, for momentarily stopping the papers so as to open up a gap between the leading edge of said one paper and the trailing edge of the paper just ahead;

cam means mounted for movement around a circular path at a speed to complete one revolution in the time required by said belt conveyor means to travel from said intercepting means to said stop means; a cam follower engageable by said cam and lifted thereby; and

means operatively connected to said cam follower and actuated thereby to remove said stop means from in front of said stack as the next succeeding gap approaches said stop means, and to insert said stop means into said next succeeding gap as the completed stack moves clear, in readiness to start the next stack.

3. Apparatus for conveying and stacking papers received from a machine into stacks of a predetermined number of copies, comprising:

a horizontal loading table;

belt conveyor means disposed to receive a continuous line of overlapping papers from said machine and transport the same to a stacking station on said loading table, said papers being initially disposed with the leading edge of each paper exposed and overlying the trailing edge of the paper ahead;

said belt conveyor means including means for inverting the line of papers so that the leading edge of each paper is overlaid by the trailing edge of the paper ahead;

stop means engageable with the leading edge of said papers as they are brought to said stacking station, whereby said papers are stopped and caused to accumulate into a stack, said papers being inserted into said stack at the bottom end thereof;

intercepting means movable into position to engage the exposed leading edge of one of said papers ahead of said stop means, for momentarily stopping the papers so as to open up a gap between the leading edge of said one paper and the trailing edge of the paper just ahead;

cam means mounted for movement around a circular path at a speed to complete one read-cycle in the time required by said belt conveyor means to insert said predetermined number of copies into a stack;

means actuated by said cam means, operable to remove said stop means as each stack is completed, and allow the same to move clear of said stacking station, said stop means being inserted into the next succeeding gap to engage the leading edge of the first paper following said gap; and

other means actuated by said cam means, operable to move said intercepting means into position to engage said papers in synchronism with the removal of said stop means, whereby the space between gaps is such that the number of papers included between gaps is equal to the number of papers going into each stack.

4. Apparatus for conveying and stacking papers received from a machine into stacks of a predetermined number of copies, comprising:

a horizontal loading table having a stacking station; a drum journaled for rotation about a horizontal axis adjacent one end of said table; an idler rotating about an axis parallel to the axis of said drum and on the side of said stacking station opposite said drum;

the top surfaces of said idler and said drum being substantially tangent to the top surface of said loading table;

a first endless belt trained around said drum and said idler, and sliding over the surface of said loading table;

a second endless belt wrapped around one side of said drum on top of said first endless belt, said second endless belt being trained around a series of rollers; said first and second endless belts cooperating to form a conveyor having a receiving end disposed to re-

75

ceive a continuous line of overlapping papers from said machine, and a discharge end disposed to deliver said papers to said stacking station, said papers being initially disposed with the leading edge of each paper exposed and overlying the trailing edge of the paper ahead;

said line of papers being inverted by said drum and delivered to said stacking station with the leading edge of each paper underlying the trailing edge of the paper ahead;

stop means movable between a retracted position and an extended position wherein the leading edges of the papers are engaged as they are delivered to said stacking station; thereby stopping said papers and accumulating the same into a stack, said papers being inserted by said conveyor into the stack at the bottom end thereof;

intercepting means movable into engagement with the leading edge of said papers adjacent the receiving end of said conveyor to hold said papers back and thereby open up gaps in the line of papers, said gaps being spaced apart from one another a distance such that the number of papers on said conveyor between gaps is equal to the number of papers going into each stack;

means operable to move said stop means from said extended position to said retracted position so as to allow the completed stack to move clear of the stacking station; and

means operable to move said intercoupling means into engagement with said papers in synchronism with the retraction of said stop means; said stop means being restored to said extended position as the next gap reaches said stacking station.

5. Apparatus as defined in claim 4, wherein said means operable to move said stop means between said extended and retracted positions comprises:

a cam mounted on said drum for rotation therewith; a cam follower engageable by said cam and operatively connected to said stop means to move the latter from said extended position to said retracted position; and

spring means operable to restore said stop means to said extended position when said cam follower has been released by said cam.

6. Apparatus as defined in claim 5, wherein said means operable to move said intercepting means into engagement with said papers in synchronism with the retraction of said stop means comprises:

a second cam mounted on said drum for rotation therewith;

a second cam follower engageable by said second cam and operatively connected to said intercepting means to move the latter into engagement with said papers; and

a second spring means operable to remove said intercepting means from its paper-engaging position when said second cam follower has been released by said second cam.

7. Apparatus for conveying and stacking papers received from a machine into stacks of a predetermined number of copies, comprising:

a horizontal loading table having a stacking station; a drum journaled for rotation about a horizontal axis adjacent one end of said table;

an idler rotating about axis parallel to the axis of said drum and on the side of the stacking station opposite said drum;

the top sides of said idler and said drum being substantially tangent to the top surface of said loading table;

a first endless belt trained around said drum and said idler, and sliding over the surface of said loading table;

a second endless belt wrapped around one side of said

drum on top of said first endless belt, said second endless belt being trained around a series of rollers; said first and second endless belts cooperating to form a conveyor having a receiving end disposed to receive a continuous line of overlapping papers from said machine, and a discharge end disposed to deliver said papers to said stacking station, said papers being initially disposed with the leading edge of each paper exposed and overlying the trailing edge of the paper ahead; 5 said line of papers being inverted by said drum and delivered to said stacking station with the leading edge of each paper underlying the trailing edge of the paper ahead; 10 stop means movable between a retracted position and an extended position wherein the leading edges of the papers are engaged as they are delivered to said stacking station, thereby stopping said papers and accumulating the same into a stack, said papers being inserted by said conveyor into the stack at the bottom end thereof; 15 means for driving said drum and said endless belts at a fixed speed ratio relative to the operating speed of said machine; 20 a cam assembly rotatably mounted on one end of said drum and having an even-numbered plurality of cam lobes that are selectively movable between operative and inoperative positions; 25 means for driving said cam at a rotational speed that is a fraction of the drum rotational speed, said fraction being the reciprocal of the number of said cam lobes on said cam assembly; 30 a cam follower operable to be lifted by any of said cam lobes that are at said operative position; means actuated by said cam follower to retract said 35 stop means from said extended position so as to allow the completed stack to move clear of said stacking station; intercepting means movable into engagement with the leading edge of said papers adjacent the receiving 40 end of said conveyor to hold said papers back and thereby open up a gap in the line of papers; and means operable to move said intercepting means into engagement with said papers in synchronism with the retraction of said stop means, the gaps thus 45 formed in said line of papers being spaced apart from one another a distance such that the number of papers between gaps is equal to the number of papers going into each stack; said stop means being restored to said extended position through the gap following the completed stack as the latter moves clear of said stacking station. 50 8. Apparatus for use with a machine to accumulate the papers delivered thereby into stacks of a predetermined number of copies, comprising: a horizontal loading table having a stacking station; a drum journaled for rotation about a horizontal axis adjacent one end of said table; an idler rotating about an axis parallel to the axis of said drum and on the side of said stacking station opposite said drum; 60 the top sides of said idler and said drum being substantially tangent to the top surfaces of said loading table; a first endless belt trained around said drum and said idler, and sliding over the surface of said loading table; 65 a second endless belt wrapped around one side of said drum on top of said first endless belt, said second endless belt being trained around a series of rollers; said first and second endless belts cooperating to form a conveyor having a receiving end disposed to receive a continuous line of overlapping papers from said machine, and a discharge end disposed to deliver said papers to said stacking station, said papers being 70 75

initially disposed with the leading edge of each paper exposed and overlying the trailing edge of the paper ahead; said line of papers being inverted by said drum and delivered to said stacking station with the leading edge of each paper underlying the trailing edge of the paper ahead; stop means movable between a retracted position and an extended position wherein the leading edges of the papers are engaged as they are delivered to said stacking station, thereby stopping said papers and accumulating the same into a stack, said papers being inserted by said conveyor into the stack at the bottom end thereof; means for driving said drum and said endless belts at a fixed speed ratio relative to the operating speed of said machine; cam means mounted on said drum and rotatable therewith, said cam means including at least one base member rotatable about an axis parallel to the axis of said drum and spaced radially therefrom; said base member having an even-numbered plurality of equally spaced cam lobes that are selectively movable between operative and inoperative positions; means for driving said base plate at a rotational speed that is a fraction of the drum rotational speed, said fraction being the reciprocal of the number of said cam lobes on said base member; a first cam follower operable to be lifted by the operatively positioned lobes of said cam follower; means actuated by said first cam follower to retract said stop means from said extended position so as to allow the completed stack to move clear of said stacking station; intercepting means movable into engagement with the leading edge of said papers adjacent the receiving end of said conveyor to hold said papers back and thereby open up a gap in the line of papers; a second cam follower operable to be lifted by the operatively positioned lobes of said cam means; and means actuated by said second cam follower to move said intercepting means into engagement with said papers in synchronism with the retraction of said stop means, the gaps thus formed in said line of papers being spaced apart from one another a distance such that the number of papers between gaps is equal to the number of papers going into each stack; said stop means being restored to said extended position through the gap following the completed stack, as each stack moves clear of said stacking station. 9. The method of accumulating papers delivered by a machine into stacks of a predetermined number of copies, said papers being delivered in a continuous line of overlapping papers with the leading edge of each paper exposed and overlying the trailing edge of the paper ahead, said method comprising the steps of: transporting said line of overlapping papers from said machine to said stacking station; inverting said line of papers prior to delivery of the same at said stacking station; momentarily interrupting the flow of papers so as to open up gaps therein at intervals spaced to include the number of copies between successive gaps equal to the number of copies allotted to each stack; inserting a barrier into said gap as it approaches said stacking station, so as to stop said papers in their travel, each paper being successively inserted under the preceding paper to form a stack; and releasing said stack as the next succeeding gap approaches said stacking station, thereby allowing the completed stack to move away from said stacking before starting a new stack. 10. The method of accumulating papers delivered by a machine into stacks of a predetermined number of

11

copies, said papers being delivered in a continuous line of uniformly spaced, overlapping papers, with the leading edge of each paper exposed and overlying the trailing edge of the paper ahead, said method comprising the steps of:

transporting said line of overlapping papers from said machine to said stacking station;
 inverting the line of papers prior to delivery of the same at said stacking station;
 momentarily engaging the exposed leading edge of one of said papers prior to inverting the same, thereby stopping the travel of the papers so that a gap is opened up in the line of papers at a distance from said stacking station such that the number of papers

between said gap and the stacking station is equal to the number of papers going into each stack; inserting a barrier into said gap as the latter approaches said stacking station, and retaining said barrier in place so as to stop said papers in their travel; building a stack of papers behind said barrier by inserting each paper successively beneath the paper ahead; and
 removing said barrier as the last paper before the next succeeding gap is inserted into the bottom of the stack thereby releasing the completed stack and allowing the same to move away from said stacking station.
